UNITED STATES PATENT OFFICE.

WILLIAM WALLACE KEMP AND WILLIAM H. VAN HORN, OF BALTIMORE, MARYLAND.

BURNER FOR GAS SINGEING-MACHINES.

1,128,791.

Specification of Letters Patent. Patented Feb. 16, 1915.

Application filed April 22, 1913. Serial No. 762,953.

To all whom it may concern:

Be it known that we, WILLIAM WALLACE KEMP and WILLIAM H. VAN HORN, citizens of the United States, residing at Baltimore, in the State of Maryland, have invented new and useful Improvements in Burners for Gas Singeing-Machines, of which the following is a specification.

This invention relates to gas using machines, more particularly to machines of the rotary type for singeing hosiery, and has for an object to provide an improved burner for such machines which may be automatically controlled by the operation of the machines.

Previously in machines of this type the flame has been burned continuously, needlessly heating the adjacent parts of the machine when the flame is not in actual use and causing waste of the fuel supplying the flame. In this type of machine the articles are fed to the flame intermittently, a considerable space of time elapsing between the feeding of the articles, and it is the object of the present invention to prevent the waste of the fuel supplying the flame during this lapse of time between the application of the articles to the flame.

In carrying out this object, the invention comprises, broadly, a valve controlling the supply of fuel to the flame, and means operated by the movable parts of the machine for opening and closing the valve so as to completely extinguish the flame or turn the flame down between the feeding of the articles so that no appreciable heat will be generated by the flame when not in actual use and the supply of fuel will be cut down to a minimum.

Another object of this invention is to provide the machine with operating means which may be adjusted to turn on or raise the flame at any desired point of the operation of the machine, and to keep the flame burning as long as desired to accommodate the machine to articles requiring different times of exposure to the flame.

Other objects and advantages of this invention will appear from the following detail description of one embodiment of this invention, and from the accompanying drawings in which—

Figure 1 is a side elevation of a conventional form of rotary singeing machine having the improved burner applied thereto. Fig. 2 is an elevation of the burner showing in section the adjacent parts of the

singeing machine supporting the burner. Fig. 3 is a detail enlarged sectional view of the singeing machine on the line 3—3 of Fig. 2. Fig. 4 is a top plan view of the 60 enlarged section of Fig. 3. Fig. 5 is a detailed enlarged longitudinal sectional view through the valve of the burner.

As illustrated in the present drawing the improved burner is applied to a rotary 65 singeing machine adapted particularly to hosiery, and in the general illustration of this singeing machine 10 designates the frame in which is mounted a transverse shaft 11 upon which is secured a relatively 70 large gear-wheel 12 driven in any suitable manner so as to rotate the shaft 11. Also mounted upon the shaft 11 is a spider 13, shown as having three radially extending arms upon the outer ends of which are 75 mounted supports 14 curved in the arc of a circle the center of which is the shaft 11. It will be noted that a considerable space is provided between the supports 14 to admit of the application of articles to be singed. 80 The frame 10 is provided with a superstructure 15 carrying at one side an inclined support 16 upon which are mounted the burner tubes 17. These burner tubes 17 may be mounted upon the support 16 in any 85 suitable manner and are shown in the present instance as being grouped in pairs and carried upon T's 18. The T's 18 extend through suitable openings in the support 16 and the tubes extend inwardly in the formation of yokes open at their inner ends for the reception of the supports 14, which are offset laterally from the arms of the spider 13. The superstructure 15, for the purpose 90 of reinforcement of the same, is provided intermediate its ends with a web 19 provided with a horizontal flange 20 turned outwardly from the web 19 to reinforce the web.

The burner of this invention, and as disclosed in the present drawings, comprises a valve casing 21 provided upon its inner side with a stud 22 fitting in a socket 23 detachably mounted on the support 16 of the superstructure and arranged below the burner 105 tubes 17. For the purpose of securing the valve casing 21 at the desired angle a set screw 24 is threaded through one side of the socket for engagement with the stud 22 so as to hold the same from turning after 110 the valve casing has been adjusted. A stem 25 is mounted in the valve casing 21 for

longitudinal movement therein, and is normally depressed by a spring 26 surrounding the upper end of the stem 25 and bearing at its lower end against the outer side of a 5 valve 27 mounted on the stem and being compressed against the valve by a cap 28 detachably secured upon the upper end of the casing 21. As shown in detail in Fig. 5 the cap 28 is provided with an upstanding 10 low projection registering with the stem 25 and adapted to receive the upper end thereof when the stem is raised against the tension of the spring 26. In one side of the casing 21, and above the valve 27, is a gas 15 inlet nipple 29 adapted for connection with a suitable source of gas supply. The casing 21 is reduced in diameter immediately below the valve 27 to provide therefor a seat 30 whereby the supply of gas through the nipple 20 29 is cut off by the seating of the valve 27 from the lower part of the casing 21. In the two-pipe valve disclosed in the present drawing the lower end of the casing 21 is provided at one side with a nipple 31 25 adapted for attachment to a suitable source of compressed air supply and the casing is provided with an internal annular shoulder or flange 32 immediately above the nipple 31 and into which a plug valve 33, mounted 30 upon the stem 25 and spaced below the valve 27, is adapted to snugly fit to close off the supply of air to the middle portion of the casing 21. The casing 21 is provided with a third nipple 34, leading from a point intermediate the valves 27 and 33, to which is 35 secured a supply pipe 35 extending to the T's 18 of the burner tubes. The stem 25 preferably extends but a short distance below the casing 21 and is provided on its 40 lower end with a coupling sleeve 36 secured to the stem 25 in the usual manner by a set screw and adapted to receive in its lower end a valve operating rod 37.

A detachable bracket 38 is secured to the 45 superstructure 15 in any suitable manner, such as by constructing the bracket 38 U-shape whereby to engage the bracket over the horizontal flange 20 of the superstructure and mounting a plurality of set-screws 50 39 in the under side of the bracket for engagement against the lower side of the flange 20 to thus secure the bracket to the web 19. Rising from the bracket 38 is a lug 40 upon which is mounted for rotatable adjustment, 55 by means of a clamping screw 41, a guiding sleeve 42 receiving the lower end of the valve operating rod 37 and admitting of the longitudinal sliding movement of the rod 37 therethrough. A second lug 43 rises 60 from the bracket 38 in spaced relation to the lug 40, and is provided with a bearing in its upper end receiving therethrough a stub-shaft 44. The stub-shaft 44 projects through the superstructure 15 and carries upon its 65 outer end a valve rod lifter 45 provided

upon its inner end with a sleeve engaging the stub-shaft 44 and adjustably fixed thereon by a set-screw 46. The outer end of the lifter 45 is flattened as shown and bears against the lower end of the valve operating rod 37 which projects slightly below the guiding sleeve 42.

The inner end of the stub-shaft 44 has fixed thereon, by a set screw 47, an arm 48 upon the outer end of which is mounted a 75 roller 49 adapted for engagement with a cam hereinafter fully described. Secured against the outer side of the gear-wheel 12, which turns with the supports 14, is a cam wheel 50 preferably made up of a number of 80 parts, shown as in two parts, whereby the cam wheel 50 may be placed around the shaft 11 without removing the shaft from the frame 10.

From Fig. 3 of the drawings it will be 85 noted that the cam wheel 50 is made up of two semi-circular parts, each of which is provided at its ends with inwardly extending lugs 51, the lugs at the meeting ends of the sections of the wheel abutting and being secured together by clamping screws 52. The wheel 50 is provided at points opposite to the spokes of the gear-wheel 12 with clamps 53, the same being shown as comprising straps one of each clamp being secured to the wheel 50 while the opposite strap of each clamp is secured across the inner side of the adjacent spoke by means of the clamping screws 54. In this manner the wheel 50 is rigidly secured upon the gear 12 and moves therewith. The periphery of the wheel 50 is smooth and is concentric to the shaft 11 and supports the rollers 49 in normal inactive position whereby the valve operating rod 37 remains at rest under the tension of the spring 26. The wheel 50 is provided at points opposite to the supports 14 with cam blocks 55 having inclined ends, as at 56, up over which the roller 49 rides as the cam wheel 50 is turned and the blocks 55 are brought into register with the roller. Each cam block 55 raises the roller and holds the roller in such raised position during the time occupied in the passage of a predetermined length of the corresponding support 14 between the burner tubes 17. The cam block 55 is of such a length that it supports the roller until the desired length of the support 14 passes from between the burner tubes 17.

The articles to be singed are of different lengths, and in order to accommodate the machine to these different length articles, and to economize the consumption of fuel, the cam blocks 55 are supplemented with supplemental blocks 57 which interfit with the cam blocks 55 and provide a continuation thereof. For the purpose of securing the blocks 55 and 57 upon the cam wheel 50 the blocks are provided with pairs of spaced 130

and inwardly extending lugs 58 straddling the rim of the wheel 50 and having screw-threaded openings therethrough for the reception of set-screws 59 adapted to extend 5 inwardly through the lugs 58 and engage against the inclined shoulder 60 on the side of the wheel 50. The wheel 50 is provided with the shoulder 60 on each side so that the set-screws 59 which are carried in the 10 opposed lugs have a substantial support for holding the blocks 55 and 57 to the wheel. The blocks 55, which are of considerable length are provided with two or more pairs of the lugs 58 so as to substantially support 15 the blocks upon the wheels. It is understood that there are a number of the blocks 55 on the wheel 50, corresponding to the number of the supports 14 on the spider, so that the valve is opened each time that a 20 support 14 is brought into the operative path of the flame issuing from the burner tubes 17.

In the operation of the burner the gear wheel 12 is rotated by any suitable means 25 whereby the shaft 11 is turned and effects the turning of the spider 13. As the gear wheel 12 is rotated the cam wheel 50 is carried therewith and the roller 49 rides freely over the periphery of the cam wheel 50. 30 When one of the work supports 14 reaches the burner tubes 17 one of the cam blocks 55 engages the roller and lifts the same from the periphery of the wheel. As the roller is lifted the arm 48 is raised, the stub-shaft 44 is turned, and the lifter 45 is moved up 35 against the lower end of the supporting sleeve 42, lifting the valve operating rod 37 against the tension of the spring 26. When the rod 37 is raised the stem 25 moves there- 40 with and lifts the valves 27 and 33 from the seat 30 and flange 32 respectively, whereby gas is admitted to the nipple 34, and compressed air is admitted to the nipple 34. The gas and air commingle and pass 45 through the supply pipe 35 to the T's 18 from which this gaseous mixture is distributed to the several burner tubes 17 where it is ignited from a pilot 17^a. The pilot 17^a, as may be seen from Fig. 2 of the drawings, 50 comprises one or more small tips located immediately above the lower burner tubes 17 and supplied continuously with gas from the common gas supply pipe 29^a by a branch pipe 17^b leading from the supply pipe 29^a 55 forwardly of the main burner supply valve 21. Thus the pilot takes its gas from the main pipe 29^a before the gas passes through the valve 21 and a steady flame is thereby maintained at the pilot 17^a. It is of course 60 understood that this is only one of many arrangements of pilots that may be used, the present disclosure being merely for the purpose of clearly illustrating the present invention. The valve is held in this open position until the cam block 55, or the sup-

plemental blocks 57 pass from beneath the roller 49. When the blocks pass from beneath the roller, the roller is permitted to drop down upon the periphery of the wheel 50 whereby the lifter 45 drops into 70 normal position and the rod 37 is released. The spring 26 forces the valves 27 and 33 closed so that the fuel supply is cut off to the burners and the small pilot 17^a alone remains burning. 75

The structure of the valve 21 may be other than shown in the drawings, since this valve forms no part of this invention except as being of a construction adaptable for use in connection with the automatic controlling means. Thus the valve may have any number of openings, may be made to supply gas from any suitable source to the burner tubes and may be different in construction. It is also understood that this 85 invention is not limited to the specific construction herein described, and shown, but this structure may be varied to accommodate the burner to machines of different forms and of a different character than 90 singeing machines, the scope of the invention being determined by the appended claims. 95

What is claimed is—

1. In a gas singeing machine and in combination, a rotary frame, a plurality of spaced apart article supports on said frame, a burner, means for rotating the frame to bring said supports one at a time into the line of the flame of the burner, and means 100 connected to the burner and to the rotary frame for supplying gas to the burner only when said supports are in the line of the flame. 105

2. The combination with a stationary frame, a rotary frame therein, a plurality of spaced apart article supports on the rotary frame, and a burner on said stationary frame in the path of said supports, of means on the stationary frame connecting 110 said burner with said rotary frame whereby to control the burner to admit gas thereto only during the travel of a predetermined length of said supports past said burner. 115

3. In a gas singeing machine, the combination with a rotary frame, spaced apart supports on the frame and a burner in the path of said supports, of gas supplying means connected between the burner and the frame and adapted to admit gas to the burner upon the registration of each support with the burner and maintain the flow of gas during the passage of a predetermined length of each support past the burner. 120

4. In a singeing machine and in combination, a frame, work supports mounted on the frame, operating means for the supports, burner tubes on the frame in the path of said supports, a valve controlling 125

the gas supply to said burner tubes and detachable means carried on said frame and said operating means and having connection with said valve whereby to control the flame 5 of the burner tubes.

5. In a singeing machine and in combination, burner tubes, a rotary frame, a plurality of article supports on the frame, means connected to the frame adapted to 10 move the supports consecutively into the line of the flame of the burner tubes, and automatic means controlled by the rotary frame connected to the burner tubes for cutting off the supply of gas to the tubes at 15 predetermined times during the movement of said supports.

6. In combination with a rotary frame, spaced apart supports on said frame and a stationary burner in the path of said supports, a valve controlling the supply of gas 20 to said burner, and means connected to said valve and to said frame for opening said valve upon the registration of one of said supports with said burner, and maintaining said valve open during the passage of a predetermined length of the support past 25 the burner.

7. In a gas singeing machine, the combination with a rotary frame, supports on the 30 frame and operating means for the frame including a driving gear, of a burner in the path of said supports, a valve regulating the flow of gas to said burner, a push rod connected to the valve for operating the 35 same, and a sectional cam member adapted for securing to said driving gear and for engagement with said push rod to operate the same.

8. In combination with a rotary singeing 40 machine having a rotary frame, a shaft for supporting the frame and a driving gear on the frame for rotating the frame, a burner in the path of the frame, a valve controlling the admission of gas to said burner, a rod 45 connected to the valve for opening and closing the same, and a sectional cam member adapted for engagement about the shaft and for securing to said drive gear to turn with the latter and operate said rod.

50 9. In a gas machine and in combination, a frame, a plurality of spaced apart article supports mounted on the frame, burner tubes on the frame, operating means on the frame having connection with said article 55 supports adapted to rotate the same and bring said supports consecutively into the line of the flame of said burner tubes, a valve controlling the supply of gas to said burner tubes, and means connected to said 60 operating means and to said valve for opening and closing the valve to reduce said flame upon the passage of articles on the supports out of the line of the flame.

65 10. In a gas using machine, the combination with a frame, burner tubes carried at

one point on the frame, a rotary frame in said first frame, a plurality of spaced apart work supports mounted on the rotary frame, and operating means for turning the rotary frame whereby to bring said work supports 70 one at a time through the space between said burner tubes, of a valve supplying gas to said burner tubes, and controlling means connected to said operating means and to the valve and adapted to cut off the supply 75 to said tubes upon the passage of a predetermined length of the work support through the space between the tubes.

11. In combination with a frame, a work support on the frame, burner tubes on the 80 frame in the path of the work support, and a gear mounted in the frame and connected with said work support for rotating the same, a valve connected to said tubes for supplying gas thereto, an operating rod connected to the valve for opening and closing the same, a lifter mounted on the frame and engaging the lower end of said rod whereby to operate the same, a pivoted arm connected to said lifter having a roller in its outer end, a cam wheel connected to said gear and lying in the path of said roller, and a plurality of detachable cam blocks mounted on 85 said wheel adapted to lift said arm and maintain the same in such position during 90 the passage of a predetermined length of the work support past the burner.

12. In a gas singeing machine, the combination with a rotary frame, spaced apart supports on the frame and a burner tube in 100 the path of said supports, of a gas supply for said burner tube, an air supply for said burner tube, a controlling valve common to said gas and air supply whereby to control the passage of a predetermined mixture of 105 gas and air to said burner tube, and operating means for the valve connected to said rotary frame adapted to open and close the same during the passage of each of said supports through the flame of the burner tube 110 whereby to intermittently feed a uniform mixture of gas and air to said tube.

13. In a singeing machine, the combination with a rotary frame, a plurality of supports on the frame, and a stationary burner tube in the path of said supports, of a gas inlet, an air inlet, a valve connecting said gas and air inlets to said burner tube and admitting a predetermined mixture of gas and air to the burner tube, and valve opening and closing means connected to the rotary frame adapted to operate said valve to admit the predetermined mixture of gas and air to said burner tube upon the registration of each one of said supports with the burner tube and to close said valve upon the passage of a predetermined length of each of said supports past a burner tube.

14. In a gas using machine the combination with a frame having a reinforcing web,

a shaft mounted in the frame, work supports on said shaft, a gear on said shaft adapted to rotate the same, and burner tubes carried on the frame in the path of said work supports, 5 of a valve carried by the frame having connection with said burner for supplying gas thereto, an operating rod depending from the valve, a detachable bracket mounted upon the web of said frame, a lifter carried by the bracket and engaging said rod, and means connected to said gear for engagement with said lifter whereby to move the same to open said valve upon the entrance of one of said work supports between 10 said burner tubes.

15. In a singeing machine and in combination, a frame, a plurality of work supports mounted in the frame, a gear in the frame connected to said supports and adapted to rotate the same, burner tubes lying in the path of said supports, a valve supplying gas to said tubes, a cam detachably secured to said gear, a rocker arm carried by the frame and lying in the path of said cam 20 whereby to rock said arm upon the rotation of said cam, and a connection between said valve and said rocker arm whereby said valve is operated upon the turning of said cam.

25 16. In a singeing machine and in combination, a frame, article supports on the frame, a gear on the frame for turning said supports, burner tubes on the frame in the line of said supports, a bracket detachably mounted on the frame, a rock shaft journaled in the bracket, a lifter mounted on one 30 end of the rock shaft, a valve controlling

the gas supply to said tubes, an operating rod connected to said valve and engaging said lifter, a sectional cam wheel, clamps on 40 the wheel engaging the gear, a series of detachable cam blocks secured upon the periphery of said cam wheel and corresponding to the number of article supports, a rocker arm carried upon the opposite end of 45 said rock shaft, and a roller upon the outer end of said arm engaging said cam wheel and said cam blocks.

17. In a singeing machine and in combination, a frame, a plurality of work supports mounted in the frame, a gear in the frame connected to said supports adapted to rotate the same, burner tubes lying in the path of said supports, a valve supplying gas to said tubes, a cam detachably secured to 50 said gear, a rocker arm carried by the frame and lying in the path of said cam whereby to rock said arm upon the rotation of said cam, a connection between said valve and said rocker arm whereby said valve is operated upon the turning of said cam to open and close the valve, and a continuously 55 burning pilot adjacent said burner tubes adapted to ignite the gas issuing from the tubes when said valve is open.

In testimony whereof we have hereunto set our hands in presence of the subscribing witnesses.

WILLIAM WALLACE KEMP.
WILLIAM H. VAN HORN.
